(57) **CLAIM**

The ornamental design for a display device, as shown and described.

DESCRIPTION

FIG. 1 is a perspective view of the display device, according to an embodiment, shown in a contracted state;

FIG. 2 is a front view thereof;

FIG. 3 is a rear view thereof;

FIG. 4 is a left side view thereof, with the right side view being a mirror image;

FIG. 5 is a top view thereof, with the bottom view being a mirror image;

FIG. 6 is a perspective view thereof, shown in an extended state;

FIG. 7 is a front view thereof;

FIG. 8 is a rear view thereof;

FIG. 9 is a left side view thereof, with the right side view being a mirror image;

FIG. 10 is a top view thereof, with the bottom view being a mirror image;

FIG. 11 is a front view thereof, shown in a contracted state;

FIG. 12 is a front view thereof, shown in an extended state;

FIG. 13 is a perspective view of the display device, according to another embodiment, shown in a contracted state;

FIG. 14 is a front view thereof;

FIG. 15 is a rear view thereof;

FIG. 16 is a left side view thereof, with the right side view being a mirror image;

FIG. 17 is a top view thereof, with the bottom view being a mirror image;

FIG. 18 is a perspective view thereof, shown in an extended state;

FIG. 19 is a front view thereof;
